[57] CLAIM

The ornamental design for a multiple size automobile cup holder or similar article as shown and described.

DESCRIPTION

FIG. 1 is a perspective view of the multiple size automobile cup holder showing my new design.

FIG. 2 is a front elevational view thereof in the closed position.

FIG. 3 is a front elevational view thereof with the base in the open position and all three rings folded down.

FIG. 4 is a side elevational view thereof showing the base and all three rings in the open position; the side opposite being a mirror image thereof.

FIG. 5 is a rear elevational view thereof in the closed position.

FIG. 6 is a rear elevational view thereof with the base and the large ring in open position and the small and medium rings folded down.

FIG. 3

FIG. 6

FIG. 2

FIG. 5

FIG. 4

FIG. 1
